UNITED STATES PATENT OFFICE

JACOB TELLER, OF CHICAGO, ILLINOIS, AND ARTHUR P. SCHULZ, OF BUFFALO, NEW YORK, ASSIGNEES TO TELLER CORPORATION, OF CHATTANOOGA, TENNESSEE, A CORPORATION OF TENNESSEE

DESIGN FOR A CABINET COOKING RANGE

Application filed October 21, 1930. Serial No. 37,332. Term of patent 7 years.

To all whom it may concern:

Be it known that we, JACOB TELLER, a citizen of the United States, residing at Chicago, in the county of Cook and State of Illinois, and ARTHUR P. SCHULZ, a citizen of the United States, residing at Buffalo, in the county of Erie and State of New York, have invented a new, original, and ornamental Design for a Cabinet Cooking Range, of which the following is a specification, reference being had to the accompanying drawings, forming a part thereof.

net cooking range with the cover raised and, Figure 2 is a similar view with the cover closed.

Fig. 3 is an enlarged fragmentary perspective view of the burner section of the cabinet range showing the cover in the raised position.

We claim:

The ornamental design for a cabinet cooking range, as shown.

JACOB TELLER.
ARTHUR P. SCHULZ.
